UNITED STATES PATENT OFFICE

139,041

DESIGN FOR A COMBINATION MAKE-UP AND CIGARETTE BOX

Nancy Gillespie Morrison, Los Angeles, Calif.

Application June 26, 1944, Serial No. 114,196

Term of patent 14 years

(Cl. D86—10)

To all whom it may concern:

Be it known that I, Nancy G. Morrison, a citizen of the United States of America and residing at Los Angeles, in the county of Los Angeles and State of California, have invented a new, original, and ornamental Design for a Combination Make-Up and Cigarette Box, of which the following is a specification, reference being had to the accompanying drawing, forming a part hereof.

make-up and cigarette box showing my new design in open position;

I claim:

The ornamental design for a combination make-up and cigarette box, as shown.

NANCY GILLESPIE MORRISON.
